CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA

METHOD AND APPARATUS FOR FRACTIONATION OF HYDROCARBONS

Application filed November 12, 1926. Serial No. 147,890.

The present improvements relate more particularly to a method and apparatus to be utilized with processes for treating hydrocarbons to produce therefrom commercial products of low boiling point range.

In the treatment of hydrocarbon vapors having different ranges of boiling points, and in an attempt to separate and separately collect products of certain ranges of boiling points, it has been found that these separated products are more or less contaminated with a substantial portion of higher and lower boiling point products, which in most instances, is undesirable.

To give an example, a gasoline cut will consist of that portion of oil distilling off from the lowest temperature up to 437° F. This cut is condensed and separately collected. The cut taken above 437° F. is known as the kerosene cut. In the ordinary apparatus the gasoline will be found to contain boiling points higher than 437° F., and the kerosene cut will be found to contain boiling points lower than 437° F. In other words, there will be some kerosene in the gasoline cut and some gasoline in the kerosene cut. Heretofore, these were known as crude cuts of kerosene and gasoline, and were redistilled to separately free the gasoline from the kerosene and to free the kerosene from the gasoline.

In recent practice, rectifying columns have been utilized to accomplish the same purpose on the first distillation, thus avoiding redistillation of these cuts.

It is understood that the above example relates to the treatment of crude petroleum containing these various fractions in a standard still. In continuous tube stills, the operation is somewhat different. In this case the total oil to be distilled off, is vaporized and the mixed vapors passed through rectifying columns or dephlegmators, and the different cuts fractionally condensed therein.

As an illustration, if it is desired to distill the gasoline and kerosene cuts from the crude oil, the crude oil is subjected to a temperature at which both of these cuts are vaporized.

These vapors having a wide range of boiling

columns where the portions having boiling points higher than kerosene are first condensed and withdrawn separately, and the remaining vapors passed to a second rectifying column in which the portions containing 55 boiling points forming the kerosene are condensed and collected separately. The remaining vapors containing boiling points forming gasoline, are then withdrawn, condensed and separately collected. In some 60 cases, it is only desirable to obtain and collect gasoline, while in other cases, it is desirable to collect separately the gasoline, kerosene, and sometimes, gas oil. The method and apparatus for fractionation hereinafter 65 described, will be found to be suitable for all of the above purposes. If more than a gasoline cut is desired, then more dephlegmating or fractionating columns may be used in proportion to the number of cuts of different 70 boiling points desired.

It will be apparent to those skilled in the art that great savings will be made by having a rectifying column so designed as to bring about an efficient separation of the different 75 fractions for use with distilling and cracking processes, which will obviate the necessity of redistilling these condensed vapors. It is highly desirable to provide a rectifying column that will efficiently function to condense therein only those portions of the vapors having boiling points higher than those belonging to the gasoline fractions, while leaving the gasoline fractions in the vapor phase to be withdrawn and separately 80 condensed.

These various objects are accomplished in the present invention by causing the vapors to ascend in a spiral path, being subjected to the action of a cooling medium. 90 The vapors which are condensed in this ascent, together with the unvaporized portions of the cooling medium, will collect in pools extending at substantial right angles to the spiral path of the ascending vapors. 95 These pools are formed by having the corrugations in the spiral element extending at right angles to the plane of said spiral.

As a further feature of the present invention, the crests of the corrugations may 100

be perforated to permit a certain amount of surplus liquid from the pools to drop therethrough to the surface of that part of the spiral element positioned immediately therewith, thus breaking up said surplus liquid and causing the liquid to pass therethrough at substantially right angles.

Other advantages and objects of the present invention will be hereinafter more particularly brought out.

In the drawings, Fig. 1 is a diagrammatic side elevational view in vertical section of a rectifying column.

Fig. 2 is a cross sectional view on line 15 2—2 of Fig. 1.

Fig. 3 is a cross sectional view taken on line 3—3 of Fig. 2.

Fig. 4 is an enlarged fragmentary sectional view taken on line 4—4 of Fig. 3.

Referring more in detail to the drawings, 20 1 designates the outer shell having the removable head 2. Disposed vertically in the height of the shell, are helices 3 contained in an inner shell 4. The outer edge of the helices is preferably solidly joined to the inner wall of the inner shell 4 so that no vapors can pass between the outer edges of the helices and the inner wall of shell 4, to prevent channelling of the vapors. A core rod 25 5 projects downwardly through the center of the helices for the purpose of forming a supporting connection, being suspended and anchored in any obvious manner. The inner shell 4 may be flanged as shown at 6 to fit 30 between the flanges of the shell 1 and removable head 2. It will be immediately apparent that when the head 2 is removed, the inner shell 4 containing the helices can be readily withdrawn, as said inner shell 4 35 hangs freely from the top of the outer shell 1. The numeral 7 designates the vapor inlet having throttle valve 8; 9 designates the liquid condensate draw-off pipe controlled by throttle valve 10. The numerals 11, 11 40 designate inlets for cooling mediums such as pressure distillate, crude oil or other liquid cooling mediums, which lines 11, 11 are controlled by valves 12, 12. The numeral 13 45 designates a vapor outlet pipe controlled by valve 14; 15 designates a liquid level gauge and 16 the approximate liquid level line in the rectifying column. At various intervals throughout the height of the helices may be 50 interposed baffles 17. As a feature of the 55 present invention, the surface of the helices is corrugated to provide corrugations 18 extending at right angles to the plane of the spiral helices.

As a further feature of the present invention, the crests of these corrugations 18 are preferably perforated as shown at 19, for a purpose hereinafter to be explained.

The operation of the rectifying column should be apparent from the foregoing description. The mixture of vapors entering

the rectifying column through the vapor inlet 7 is discharged into the bottom section of the helices 3. It is to be noted that the liquid level shown in the drawing at 16 is just below this vapor inlet line, but sufficiently high so as to cause the lower portion of the helices to be submerged therein.

The object of this is to keep the portion below the helices filled with liquid, and thus prevent any vapors entering that section.

It is understood of course, that the apparatus can be operated efficiently without any liquid level at all in this part of the tower, if desired. As the vapors are forced to pass upwardly in a spiral path around the helices,

they are decreased in temperature, and condensation of part of the vapors continuously takes place. By the time those vapors which are still uncondensed reach the top of the helices, all of the vapors having boiling points higher than those desired, have been condensed.

Therefore, the vapors withdrawn from the rectifying column through the pipe 13 are of the desired low boiling point range. The condensate in the rectifying column contains more or less all that portion having boiling points higher than those it is desired to condense in the rectifying column, but as these condensed vapors flow back down the surface of the helices,

they collect in pools behind the corrugations 18, the surplus liquid overflowing through the apertures 19 into the helices below, and as this liquid continues to flow down, it is progressively subjected to higher heat so that

any low boiling point portions contained therein are revaporized by the hot ascending vapors. By the time the condensate reaches the bottom of the spiral, it has been freed of substantially all those fractions having the desired low boiling point range.

The function of the baffles 17 is to direct the vapors to the outer periphery of the spiral.

It is to be noted that the spacing of the spiral gradually grows smaller in an upward direction for the reason that since part of the vapors are condensed as they pass upward through the spiral, the remaining volume of vapors is smaller, and to maintain the same velocity, it is necessary to decrease the space

between the helices. It is of considerable advantage to have the helices 3 made of a thin metal of great heat conductivity so that the heat from the ascending vapors can be readily transmitted from one side of the spiral to the pools of liquid collecting on the upper side, thus promoting evaporation of the light ends of this condensate.

If the oil used as charging stock contains more or less of a product having boiling points similar to those produced by cracking, this charging stock may be fed directly into the fractionating column through either of the inlet pipes

11, but it is preferable that this charging stock be preheated and brought to the tem-

100 105 110 115 120 125 130

perature of the vapors in this part of the rectifying column before being discharged therein. The rectifying column may be maintained under atmospheric pressure, su-
5 peratmospheric pressure, or under vacuum.

The rectifying column should be so de-
signed that the velocity of the vapors through
the spiral will not be sufficient to pick up by
entrainment any substantial portion of the
10 condensate.

The fractionating column may be say, five
feet in diameter more or less, and forty feet
high more or less. The spacing at the lower
15 part of the spiral may be say eight inches
more or less, progressively decreasing until
the spacing at the upper part of the spiral
is say, five inches more or less.

The advantage of permitting pools of cool-
ing liquid and condensate to be formed be-
20 yond the corrugations 18 is to utilize the heat
from the vapors passing under and over these
pools to reboil and vaporize the lighter frac-
tions trapped in these liquor pools.

Where the surplus liquid drops through
25 the perforations 19, it drops at right angles
to the ascending vapors.

By providing perforations 19 in the top
of the corrugations 18, I overcome the objec-
30 tion of having the holes clogging, which is
frequently the case where the holes are in
the bottom of the pan, which holes become
clogged with scales and the like, thus closing
them. At the same time, by providing the
35 holes in the top of the corrugations, I permit
a pool of oil to collect back of each corru-
gation to stabilize the temperature through-
out the dephlegmator, and as hereinafter ex-
plained, permit reboiling and vaporization
40 of light fractions trapped in said liquid pools.
It is understood of course, that these corru-
gations 18 can be made sufficiently high to
form whatever size pool it is preferable.

The charging stock treated per day may be
45 one thousand barrels, and the vapors enter-
ing the rectifying column through the pipe
7 may be at a temperature of say 830° F.
more or less, while the vapors discharging
through the pipe 13 may be at a temperature
50 of say 350° F. more or less, these figures of
course, being merely illustrative.

I claim as my invention:

1. An apparatus for rectifying hydrocar-
bon oil vapors comprising an elongated ver-
tical shell, a vapor inlet adjacent the lower
55 portion of said shell, a vapor outlet adjacent
the upper portion of said shell, a continuous
helical baffle within said shell, radial corru-
gations in said baffle, and perforations in the
crests of said corrugations.

60 2. A method for dephlegmating hydrocar-
bon oil vapors which comprises causing the
vapors to ascend through a fractionating
zone in a continuous helical path in counter-
current heat exchange relation with a de-
phlegmating liquid descending in a helical

path through said fractionating zone, collect-
ing the liquid in a series of pools during its
helical descent through said zone, overflowing
liquid from the pools into direct contact with
the rising vapors therebelow, removing said
70 liquid and condensate from the lower por-
tion of said zone, and removing the uncon-
densed vapors from the upper portion of said
zone.

3. A method for dephlegmating hydrocar-
bon oil vapors which comprises causing the
vapors to ascend through a fractionating
zone in a continuous helical path in counter-
current heat exchange relation with a de-
phlegmating liquid descending in a helical
80 path through said fractionating zone, collect-
ing the liquid during its helical descent
through said zone in a series of pools extend-
ing radially from the center of said zone to the
periphery thereof, overflowing liquid in dis-
85 tributed form from the pools, into direct
contact with the rising vapors therebelow,
removing said liquid and condensate from
the lower portion of said zone, and removing
the uncondensed vapors from the upper por-
90 tion of said zone.
